CLAIM

The ornamental design for a card case, as shown and described.

DESCRIPTION

FIG. 1 is a top plan view of a card case, showing our new design, the bottom plan being a mirror image thereof;

FIG. 2 is a side elevation view, the opposite side being a mirror image thereof;

FIG. 3 is a top plan view, showing the card case in closed condition, the opposite side being a mirror image thereof; and,

FIG. 4 is a side elevation view in closed condition, the opposite side being a mirror image thereof.

FIG. 1

FIG. 2

FIG. 3

FIG. 4
